POWER OPERATED CONTROL FOR DRAFT REGULATORS

Clarence H. Morrow, Shaker Heights, Ohio, assignor to The Hotstream Heater Company, Cleveland, Ohio, a corporation of Ohio

Application April 6, 1933. Serial No. 664,794

5 Claims. (Cl. 236—45)

This invention relates to power closing means for automatic draft control dampers. In such a draft regulator the shutter has associated weights whereby its opening and closing draft-controlling adjustment is automatic, and has carefully predetermined characteristics; and such automatic action is the usual one of the damper. However, under certain temporary conditions, such as during a firing period, it is necessary that the shutter be closed.

The objects of this invention are to provide power means for closing of the damper by the operator from a convenient location which may be removed from the damper.

The shutter is mounted upon a sloping axis, at the end of an air inlet pipe; and various installation conditions require that the device be mountable with the axis sloping in either of the two possible directions. A further object of the invention is to provide that the described closing adjustment may be had regardless of the direction of slope and without any alteration to the device itself other than its mere installation.

Further objects are to accomplish the described results by simple inexpensive and reliable means, in compact arrangement.

The exact nature of this invention together with further objects and advantages thereof will be apparent from the following description taken in connection with the accompanying drawing, in which Fig. 1 is an assembly view of an embodiment of the invention in a typical automatic damper installation, the parts being shown as in open position, to permit automatic damper operation; Figs. 2 and 3 are enlarged details of the means providing operator control of the damper, Fig. 2 being a front elevation with parts broken away to show details of construction and Fig. 3 being a section as in the plane of line 3—3, Fig. 2; Fig. 4 is an elementary wiring diagram illustrating the connections for control of the motor.

With reference now to the drawing, the principal parts of the damper are an annular base 1 and a shutter 2 adapted to close the opening thereof.

The base 1, preferably a casting as indicated, is adapted to be secured within the mouth at the end of the pipe through which flow is to be controlled.

The shutter 2 which may preferably be of sheet metal as indicated, reinforced as by the peripheral flange 2a and nondiametrical rib 4, is mounted for free swinging movement about an axis in the plane of the base, in one direction

from said plane. The axis of swing, as indicated by the line A—A, is nondiametrical and preferably adjacent the rib 4, and further details of the exact arrangement by which the shutter is mounted are immaterial here.

The shutter thus has a long side B and a short side C extending from the axis. That the long side B may swing inwardly only, from the plane of the base 1, while the short side C may swing outwardly only therefrom, the base is provided with a flange 5 overlying the side B and a flange 6 underlying the side C. The shutter is preferably weighted by means not shown and forming no part of this invention, to give it predetermined opening and closing characteristics provided the axis A—A have the proper slope; and that this slope may be accurately attained when mounting the device, the front face of the base 1 is provided with indexing indicia as indicated Fig. 1. There are two sets of such indicia, providing for plumbing of the base in either of two positions depending on the direction of draft, wherein the axis A—A has slope in opposite directions.

What has thus far been described is not new in the art and will be found further disclosed in my copending application, Serial No. 658,393, filed September 24, 1933, and it will be appreciated that when properly mounted in either of the two positions and under the usual conditions, the shutter will float in partly opened positions automatically adjusting itself to provide the proper flow through the pipe to the end of which it is attached.

According to this invention I provide means for closing the shutter when desired. The principal parts of the device of the invention are a crank member 7, a flexible connector 8 arranged to be effective between the free end of the crank 7 and the long side B of the shutter, guide means for the connector 8, a motor 9, means for driving the crank by the motor, and control connections for the motor.

The connector 8 may be simply a chain, of the type indicated wherein each link has swivel connection with the adjacent links. It is secured with the shutter as at 10, preferably approximately centrally of the area of the long shutter side B. The opposite end of the connector is joined to the crank by a swivel mounted fitting 7a.

The guide means comprises a bracket 11 mounted upon the base 1 as by screws 12, extending inwardly of the base and carrying an end pulley 13 and a pair of pulleys 14, with a cover plate 15 overlying the pulleys, the ar-

angement providing a guide opening for the connector 8 aligned with the connection 10, having a bend over the pulley 13, and leading between the pulleys 14 to the end of the crank 7 when the latter is in the position shown in the drawings.

The crank shaft 16 bears in the bracket 11 adjacent the base 1 as indicated, so that the path of the crank partly overlies the shutter 8 but extends outwardly beyond the base 1, in a plane spaced from that of the base, the bracket 11 being disposed between these planes.

The parts are so proportioned and arranged particularly as to the lengths of the connector 8 and the crank 7, that when the crank is in the position illustrated, the shutter will be free to swing in automatic operation as far as is necessary, whereas if the crank be moved to a position 180° removed from that illustrated, it will 20 actuate the connector 8 to close the shutter.

The bracket 11 has a part 17 extending beyond the base 1, and the motor 9 is secured to this bracket part 17 as by screws 18, and the motor is thus positioned alongside the pipe on which the base may be mounted, underlying the outer part of the crank throw similarly as the pipe underlies the inner part of the crank throw.

Driving connections carried by the bracket are 30 provided from the motor to the crank. As here shown these connections include a pair of helical gears 19 connecting the motor shaft with an intermediate shaft 20 carrying a worm 21, which worm meshes with a wheel 22 secured on the crank shaft 16. The bracket casting and particularly its part 17 is formed to enclose and protect these driving parts as indicated Figs. 2 and 3.

That the motor may be automatically stopped 40 when the crank attains its described open and shut positions with reference to its effect upon the shutter, switch means 23 are arranged in the motor circuit, and timing means arranged to automatically throw the switch 23 dependent 45 upon the position of the crank 7. For this purpose a bilobed cam 24 is secured upon the crank shaft 16, a plunger 25 mounted in the bracket 11 to provide a follower for the cam 24, and the switch 23 arranged to be actuated by the strokes 50 of the plunger 25 thus provided, the switch box being mounted on the bracket 11 as indicated Figs. 2 and 3.

The switch 23 is illustrated conventionally only, in Fig. 4. It is preferably of the well known and commercially common push-button-actuated run-around type wherein repeated depression of a push button effects alternate throw of the switch proper between two positions. The switch has three connections as indicated Fig. 4 so that in operation it alternately contacts a common central connection 26 with two other connections 27.

A second switch 28 which may be of the same type as the switch 23, is arranged convenient to the operator, and the two switches 23 and 28 wired with the motor 9 and the line L1, L2, as shown Fig. 4. The wiring arrangement and particularly that of the switches will be recognized as that known as three-wire for two station control, wherein the motor may be started at any time by a throw of the switch 28, regardless of the position of the switch 23, and may thereafter be stopped at any time, by a throw of the switch 23.

Thus in the arrangement described, assuming

the crank 7 in the position indicated, if the operator at the remote location of the switch 28 throws his switch, the motor will be started and the crank thus caused to move. As the crank completes a 180° throw the cam 24 will act upon the plunger 25 to throw the switch 23 thus automatically stopping the motor and consequently the crank. By these operations the damper will be closed and so secured. Thereafter when it is desired to release the damper, a return throw of the switch 28 will restart the motor, move the crank 7 in the same direction until it resumes its first position, whereupon the cam 24 will rethrow the switch 23 to stop the motor. It will be observed that the motor 9 has unidirectional operation as has the crank 7, which direction, however, being immaterial.

While the crank moves from open to closed position, the connector 8 will be drawn through its guide pulleys in the direction of the crank. As the crank returns to open position, if the damper does not immediately open, the slack of the connector will lie between the crank and the guide as indicated by the bight 29, Fig. 1. When the damper automatically opens thereafter the slack will move to the other side of the guide pulleys and will lie between the guide and the shutter. The guide being spaced somewhat from the shutter there is ample clearance for a bight in this position. It will be observed that the connector 8 is bent about one or the other of the pulleys 14 dependent upon the position of the crank 7.

In Fig. 1 the device is shown mounted for a left-hand draft, the axis A—A and the actuating parts having a corresponding slope.

Should the base 1 and parts carried thereby be mounted for right-hand draft, wherein these slopes are reversed left to right, nothing else need be changed. The operation of the actuating device including its switch means will be exactly as before and with identical effect, except that of course the bight 29 will then lie on the other side of the guide means.

What I claim is:

1. In an automatic damper of the class described and having an annular base adapted to be secured to the pipe through which flow is to be controlled and a shutter mounted in said base for free swinging movement from the plane thereof, power means for closing said shutter at the will of the operator and including a motor carried by said base, a crank member driven by said motor, a flexible connector associating said shutter with said crank member, and guide means for said connector, effective thereon between its said connections.

2. In an automatic damper of the class described and having an annular base adapted to be secured to the pipe through which flow is to be controlled and a shutter mounted in said base for free swinging movement from the plane thereof, power means for closing said shutter at the will of the operator and including a motor, a crank member driven by said motor, a flexible connector associating said shutter with said crank member, guide means for said connector extending inwardly of said base and thereopposite means mounting said motor outside said base.

3. In an automatic damper of the class described and having an annular base adapted to be secured to the pipe through which flow is to be controlled and a shutter mounted in said base for free swinging movement from the plane

thereof, power means for closing said shutter at the will of the operator and including a crank member arranged to swing in a plane overlying said base, motor means in driving association with said crank member, a flexible connector associating said shutter with said crank member, and guide means for said connector arranged between said shutter and crank member and beyond the path of the latter, said parts being so proportioned and arranged that said path overlies said shutter and said motor means.

4. In an automatic damper of the class described and having an annular base adapted to be secured to the pipe through which flow is to be controlled and a shutter mounted in said base for free swinging movement from the plane thereof, power means for closing said shutter at the will of the operator and including motor means arranged alongside said pipe, a crank member arranged to have its path extend over said base and said motor means, means for driving said crank member by said motor means, a flexible connector associating said shutter with said crank member, guide means for said connector, the parts being so proportioned and arranged that said connector may be actuated to close

said shutter by a 180° throw of said crank member, driving connections for said motor and switch means associating said crank member and motor to automatically stop the motor dependent upon positioning of said crank member to close or release said shutter.

5. In an automatic damper of the class described and having an annular base adapted to be secured to the pipe through which flow is to be controlled and a shutter mounted in said base for free swinging movement from the plane thereof, power means for closing said shutter at the will of the operator and including a crank member mounted on said base to swing between positions extending radially inwardly and outwardly respectively of the base, a flexible connector associating said crank member with said shutter for closing the latter by motion of the former, guide means for said connector extending between said shutter and the path of said crank member, motor means for said crank member, means mounting said motor means on said base to be positioned alongside said pipe opposite said guide means, and driving means connecting said motor with said crank member.
